THREAD CUTTER AND CLAMP FOR LOOMS

George A. Irons, Worcester, Mass., assignor to Crompton & Knowles Loom Works, Worcester, Mass., a corporation Massachusetts

Application July 29, 1942, Serial No. 452,734

3 Claims. (Cl. 139—264)

This invention relates to improvements in thread cutters and clamps for looms and it is the general object of the invention to provide a mechanism of this type which will permit early cutting at the selvage after a weft replenishing operation of the loom.

When the depleted bobbin is expelled from a shuttle the thread extending from it to the adjacent selvage must be cut to prevent it from being drawn into the warp shed. It is customary to provide a cutter and clamp between the shuttle box and the selvage controlled so as to operate at the time of replenishment. The selvage trimmer or cutter is customarily mounted on the temple but does not usually operate until several picks after replenishment. If a second replenishing operation occurs before a previously clamped thread is cut at the selvage there is danger that the first thread will be whipped into the warp shed. It is an important object of my present invention to provide a thread cutter operating in such a way as to move the thread to be cut far enough forwardly to insure its entry into the range of action of the temple cutter on the replenishing beat of the loom or very shortly thereafter.

It is necessary that the thread of the outgoing bobbin be severed near the shuttle box mouth early in the forward motion of the thread cutter, but when the cutter operates at such time it still has considerable movement before returning to normal forward position. It is another object of my present invention to provide a yieldable operating mechanism for the pivoted cutter blade which will cause the latter to operate while near its rearmost position and then yield to permit a considerable amount of forward motion thereafter.

The form of thread cutter generally used on the heavier type of multicolor weft replenishing loom employs a pivoted carrier moved from normal front to operating rearward position by a connection from a shaft having two angular positions determined by a spring lock. The previously mentioned yielding element which permits the enlarged forward motion of the cutter normally acts on the pivoted carrier in a direction tending to cause oscillation of the control shaft. It is another object of my present invention to effect closing of the pivoted blade by a yielding element which exerts less turning force on the controlling shaft than that exerted by the spring lock.

It is a further object of my present invention to provide means for moving the cutting and clamp-

ing unit forwardly at a rate faster than that of the lay. The unit is moved to rear position while the lay is still a considerable distance behind front center so that the thread extends obliquely from the selvage into the shuttle box. As the lay advances the thread moves toward a position parallel to the fell and therefore slackens. I use a resetter for the unit mounted on the lay in such position as to engage the unit carrier between its pivot and the unit and therefore effect cutting before the thread slackens sufficiently to fall out of cutting position.

With these and other objects in view which will appear as the description proceeds, my invention resides in the combination and arrangement of parts hereinafter described and set forth.

In the accompanying drawings, wherein a convenient embodiment of my invention is set forth,

Fig. 1 is a side elevation of the lower part of a weft replenishing mechanism as viewed from the center of the loom and having my invention applied thereto in normal position.

Fig. 2 is a front elevation of the mechanism shown in Fig. 1 on an enlarged scale.

Fig. 3 is an enlarged detailed view of certain parts of Fig. 1 showing the cutter and clamp in rearward position.

Fig. 4 shows the pivoted cutter blade in open position relation and its stop, and

Fig. 5 is a diagrammatic plan view showing the manner of operation of my invention.

Referring to Fig. 1, I have shown a loom frame 10 having a magazine M preferably of the multicolor type and provided with the usual transerrer arm 11 carrying a latch 12 to be positioned for transfer by downward motion of rod 13. The lay 15 swings backwardly and forwardly for each pick of the loom and is provided with a shuttle box 16 to receive a shuttle S. A bunter 17 on the lay cooperates with latch 12 when raised on a forward beat on transferring picks to cause downward movement of the transerrer arm so that a reserve bobbin B in the magazine can replace the bobbin B' in the shuttle S. During transfer a thread T extends from the selvage of the fabric F into the shuttle box 16 and is attached to the bobbin B'. Unless this thread T is cut there is danger that it will be drawn into the warp shed and my invention relates to means to cut this thread T adjacent to the shuttle box 16.

Secured to the magazine is a stand 20 having a stud 21 on which is pivotally mounted a bell crank 22 the rearwardly extending arm of which is connected to the lower end of a link 23. The depending arm of lever 22 carries a pivot pin 25

on which is mounted a carrier 26 having a stop 27 held against a second stop 28 on the bell crank lever by a relatively heavy compression spring 29. The forward or right end of spring 29, as viewed in Figs. 1 and 3, engages an upwardly extending arm 30 on the carrier 26, while the rearward end of the spring enters a pocket in lever 22. The purpose of the spring 29 is to permit forward yielding of the carrier with respect to bell crank lever to avoid breakage should the carrier be engaged by a misplaced shuttle.

The lower end of the carrier 26 is provided with a rearwardly and horizontally extending foot 35 to which is secured a stationary cutter blade 36 and on which is pivoted a movable cutter blade 37. The left end of the fixed cutter blade 36, see Fig. 4, is held in position on foot 35 by a screw 38, and its right end may be secured to the foot in any approved manner. A block 39 serves as a stop for pivoted blade 37 and is held to foot 35 by screw 38. The movable blade swings about a stud 40 secured to the foot 35 and on which is slidably mounted a clamp plate 41 the rear end of which is guided by a pin 42 extending laterally from the foot 35. The blade 37 moves between the stationary blade 36 and the clamp 41, cooperating with blade 36 to cut the thread and coacting with the clamp plate 41 to hold that part of the thread extending to the fabric. The clamp 41 may be held against the pivoted blade by means of a spring 43 secured to the carrier 26.

Blade 37 has a forwardly extending finger 45 pivoted as at 46 to a rod head 47 adjustable on the lower end of an operating rod 48. The upper end of rod 48 slides through a pivoted or swiveled bearing 50 rockable about a pin 51 on the support 20. The bearing 50 swings about its axis 51 as the angle of the operating rod changes and the rod is slidable through the bearing.

The loom frame is provided with a temple 55 extending along the right selvage of the fabric to a point spaced a slight distance in advance of the fell 56 of the cloth. The thread T extends from the intersection of the fell and selvage into the shuttle box but is ordinarily behind the range of action of the temple cutter 57 since the latter is set several picks in advance of the fell of the cloth. The lay operates a temple cutter in usual manner on each forward beat.

As shown in Fig. 2 the upper end of link 23 is pivoted to an arm 60 secured to a shaft 61 rockably mounted on the magazine frame. A spring or yielding lock L is provided to hold the shaft 61 in either of two positions and this lock includes an arm 62 secured to the shaft 61 and having pivotally mounted thereon a block 63. A lever 64 pivoted on the magazine frame at 65 is slotted to receive the block and supports a comparatively heavy compression spring 66 the lower end of which acts on the left arm of lever 64 as seen in Fig. 2, while the upper end of spring acts on the block 63. The right arm of lever 64 is provided with a stop screw 67 for engagement with a stop lug 68 on the magazine frame, while the left arm of lever 64 carries a second stop screw 69 for engagement with the lug. By reason of the spring 66 and the stop screws on lever 64 shaft 61 is held yieldingly in one or the other of its extreme positions. Under normal conditions the parts are in the position shown in Fig. 2 with arm 60 down and screw 69 against the lug. When a replenishing operation is indicated, however, shaft 61 is turned in a clockwise direction as viewed in Fig. 2 by mechanism not shown to raise

arm 60 and link 23 and rock lever 64 so that screw 67 is against the stop lug.

The mechanism thus far described, except the stop 39, is of common construction and may be made and operated as set forth in prior Patent No. 1,633,648.

In carrying my present invention into effect I provide the lay with a resetting screw 75 positioned for engagement with the carrier 26 when the latter is in its rearward position. I also provide a rod 43 with a collar 76 below bearing 50 and held in adjusted position on the rod by a set screw 77, and surround that part of the rod lying between the collar and the bearing 50 with a comparatively light compression spring 78. A second stop collar 80 is secured in adjusted position on rod 43 above bearing 50, and screw 38 holds a stop 39 above and in the path of pivoted blade 37 to engage and arrest movement thereof in a clockwise direction as viewed in Fig. 4. Stop 39 and the parts on and connected to rod 43 are so located that spring 78 is always under some compression.

Under normal conditions the parts are in the position shown in Fig. 1 with the carrier 26 held in forward position by the spring lock L. The pivoted blade 37 is in closed position and against stop 39, and spring 78 is under maximum compression, exerting a force through rod 43 tending to move the carrier 26 rearwardly. This force, however, is much less than that exerted by the spring 66 and the parts are therefore maintained as shown in Fig. 1. Collar 80 is spaced above bearing 50, and latch 12 is below the path of bunter 17. Furthermore, carrier 26 is in front of the forward end of the path traversed by resetting screw 75.

When a replenishing operation of the loom is called by mechanism not shown herein but well understood, shaft 61 will rock to the right as viewed in Fig. 2 to lift link 23 and move the carrier 26 to its rearmost position shown in full lines in Fig. 3, while the lay is far enough back to prevent interference between screw 75 and carrier 26. During rearward movement of the carrier 26 rod 48 will descend through bearing 50 with accompanying expansion of spring 78. Collar 80 will eventually engage bearing 50 after which continued rearward movement of the carrier 26 will cause the blade 37 to rock on its axis 49 away from stop 39 to the open position shown in full lines in Fig. 3. As the lay advances the thread T will move fully in to the bight between blades 36 and 37, after which the resetting screw 75 will engage the carrier 26 and move the latter forwardly to cut the thread T and release that part of the latter extending from the blade 36 to the shuttle and grip between blade 37 and clamp 41 that part of the thread T extending from blade 36 to the selvage. Because of the location of center 24 and screw 75, the cutter moves forwardly faster than does thread T and the lay. Thread T therefore has little chance to slacken due to advance of the lay before being cut. Spring 78 will expand to provide the cutting and clamping force which actuates the blade 37 and will move the latter against the stop 39, while collar 80 is against bearing 50. Further angular movement of the blade 37 with respect to the carrier is prevented by stop 39, and as the carrier 26 continues to advance spring 78 undergoes compression by upward movement of rod 48 through bearing 50 as collar 80 rises from the bearing. The resetting screw 75 moves carrier 26 positively to a position which will throw the

lock L somewhat past its center, after which the spring 66 will complete left hand movement of shaft 61 and finish the downward motion of link 23 and forward motion of carrier 26. In the final stages of resetting spring 78 will undergo its maximum compression, but as already mentioned it is too weak to unseat the lock L which controls the position of shaft 61 and the carrier 26.

In similar thread cutters heretofore employed an attempt to give the carrier 26 an enlarged forward motion would result in movement of the rear end of the pivoted blade 37 upwardly out of clamping relation with respect to the plate 41 and the thread T extending to the selvage would be prematurely released. By providing the stop 39 I arrest movement of the blade 37 early in the forward swing of carrier 26 in such position as will preserve clamping of the thread, and the remaining forward motion of the carrier 26 can occur because of compression of the spring 78.

It is desirable that the carrier have a considerable forward movement as will be understood from Fig. 5 where it will be seen that position I corresponds to the normal forward position of the carrier 26 shown in Fig. 1, while position II corresponds to the rearmost position shown in full lines in Fig. 3. The cutter operates early in the return or forward strokes of the carrier at some such position as indicated at III in Fig. 5. When the cutter is in extreme forward position the thread T will extend rearwardly at a sufficient angle with respect to the selvage to enter the range of action of the temple cutter 57. The latter will therefore operate promptly to cut the thread near the cloth before a second replenishing operation.

From the foregoing it will be seen that I have provided simple means for effecting thread cutting early in the forward movement of the cutter and clamp unit and thereafter move the unit forwardly a sufficient distance to move thread T into the range of action of temple cutter 57. It will be noted that spring 78 is sufficiently strong to give the blade 37 its operating movements but is not strong enough to unseat the lock L as maintained by the spring 66 when the parts are in normal position. It will further be seen that the collar 83 engages bearing 59 and causes rod 43 to open the cutter 37. It will further be noted that the resetting screw 73 is so located to move the cutter and clamp unit forwardly at a rate faster than the advance of the lay to effect cutting of the thread T while it is still taut and before it slackens sufficiently to fall out of cutting position.

Having thus described by invention it will be seen that changes and modifications may be made therein by those skilled in the art without departing from the spirit and scope of the invention and I do not wish to be limited to the details herein disclosed, but what I claim is:

1. In thread control mechanism for a weft replenishing loom having a lay and operating with a shaft controlled by a spring lock and movable from normal to transfer position against the

action of the lock preparatory to a replenishing operation of the loom and thereafter returning to normal position, a pivoted carrier connected to the shaft to move therewith from normal to transfer position and back to normal position, a thread cutter and clamp unit on the carrier including a blade pivoted to the carrier between a second cutter and a clamp on the carrier, an actuator on the lay to engage the carrier between the cutter and clamp unit and the carrier axis when the carrier is in transfer position to move said carrier toward normal position, and operating mechanism connected to the pivoted blade to move the latter to closed position during the first part of the movement of the carrier caused by engagement thereof by the lay actuator.

2. In thread control mechanism for a weft replenishing loom provided with a shuttle from which extends a thread, the loom having a lay and operating with a shaft controlled by a spring lock and movable from normal to transfer position against the action of the lock preparatory to a replenishing operation of the loom and thereafter returning to normal position, a pivoted carrier connected to the shaft to move therewith from normal to transfer position and back to normal position about an axis vertically displaced from said thread, a thread cutter and clamp unit on the carrier substantially at the level of said thread and including a blade pivoted to the carrier, means on the lay to engage the carrier between the level of said thread and the carrier axis during forward movement of the lay when the carrier is in transfer position to move said carrier toward normal position, and operating mechanism connected to the pivoted blade to give the latter a cutting movement toward closed position during the first part of the movement of the carrier caused by engagement thereof by said means.

3. In thread control mechanism for a weft replenishing loom provided with a shuttle from which extends a thread, the loom having a lay and operating with a shaft controlled by a spring lock and movable from normal to transfer position against the action of the lock preparatory to a replenishing operation of the loom and thereafter returning to normal position, a pivoted carrier connected to the shaft to move therewith from normal to transfer position and back to normal position about an axis vertically displaced from said thread, a thread cutter and clamp unit on the carrier substantially at the level of said thread and including a blade pivoted to the carrier, means to move the carrier forwardly from transfer position to normal position at such a rate as to move the unit forwardly faster than that part of the lay at said level of the thread as the lay advances, and operating mechanism connected to the pivoted blade to cause the latter to cut said thread during the first part of the forward movement caused by said means.

GEORGE A. IRONS.
